May 10, 1927.

N. E. COVEL

1,628,121

PACKAGE

Filed July 9, 1925

Fig. 1.

Fig. 2.

Inventor

Nathan Edwin Covell

By

Knight Bros

Attorneys

UNITED STATES PATENT OFFICE.

NATHAN EDWIN COVEL, OF NEWTONVILLE, MASSACHUSETTS.

PACKAGE.

Application filed July 9, 1925. Serial No. 42,537.

It is customary in the confectionery trade to pack candy and the like in special boxes, designed for seasonal events, such as Thanksgiving, Christmas, etc. Such boxes are decorated in a manner appropriate to the particular occasion, and, after the occasion has passed, the merchant may find himself with a stock on hand, which, to render salable, must be removed from the special boxes and sold in bulk, or repacked, or disposed of in some other manner. In any event, considerable annoyance and expense is involved, and it is the object of the present invention to avoid this in a novel and effective manner.

The invention consists, briefly, in the provision of a special cover, decorated appropriately to a desired occasion, which may be placed over ordinary stock containers. The cost of such covers is negligible, and as they need only be applied as required, all loss is avoided and any surplus may be carried over from one season to another without any deterioration.

In the accompanying drawings, Fig. 1 shows a stock container, consisting, as a matter of illustration, of a wrapped box, the auxiliary cover according to the present invention being shown in the position of application;

Fig. 2 is an end view of the assembly, the auxiliary cover being shown in section.

The stock container A is of general utility, its decoration, if any, being of no particular seasonal significance. The auxiliary cover B, however, is of specific decorative value, being appropriate to the Thanksgiving season, as shown by way of example, and fits closely over the container A so as to give the impression of a unitary package. A ribbon, or the like, C may be tied about the two.

It is to be understood that the container or package A is complete in itself and that the cover B is merely an auxiliary thereto. As shown, the package A consists of a wrapped box of confectionery, the wrapper 45 bearing the name of the manufacturer and any desired ornamentation of general significance. The cover B, Fig. 2, consists of a frame b' of cardboard or the like having a wrapper b^2 of paper or the like applied 50 thereto. The special design is, of course, applied to the wrapper b^2 .

I claim:

1. The combination with a package consisting of a box filled with gift articles, having an outer covering displaying suitable information to indicate the nature of the gift articles, of an auxiliary cover adapted to be placed over said outer covering, and displaying information relative to some special occasion, whereby the package may be sold as a gift package, with reference to the special occasion, with said auxiliary cover in place, or as a standard staple package when the auxiliary cover is removed. 65

2. As an element of a mercantile package, a box designed to be filled with gift articles, and having an outer covering, displaying suitable information to indicate the nature of said gift articles, and an auxiliary cover 70 displaying information relative to some special occasion, and adapted to be placed over said outer covering whereby the box may be used in forming a package adapted to be sold as a gift package with reference to 75 the special occasion when said auxiliary cover is in place, and as a standard, staple package when the auxiliary cover is removed.

In testimony whereof the foregoing specification is signed.

NATHAN EDWIN COVEL.